CLAIM

The ornamental design for a cosmetic eye lash fan, as shown and described.

DESCRIPTION

FIG. 1 is a perspective view of cosmetic eye lash fan showing my new design in a first embodiment;
FIG. 2 is a front view thereof;
FIG. 3 is a rear view thereof;
FIG. 4 is a top view thereof;
FIG. 5 is a bottom side view thereof;
FIG. 6 is left side view thereof;
FIG. 7 is a right side view thereof;
FIG. 8 is a perspective view of the cosmetic eye lash fan of FIG. 1 shown in an environment of use on an eye lid;
FIG. 9 is a perspective view of cosmetic eye lash fan shown in a second embodiment;
FIG. 10 is a front view thereof;
FIG. 11 is a rear view thereof;
FIG. 12 is a top view thereof;
FIG. 13 is a bottom side view thereof;
FIG. 14 is left side view thereof;
FIG. 15 is a right side view thereof; and,
FIG. 16 is a perspective view of the cosmetic eye lash fan of FIG. 9 shown in an environment of use on an eye lid.
The broken lines shown in FIG. 8 and FIG. 16 depict environment and form no part of the claimed design.

1 Claim, 8 Drawing Sheets
